(57) **CLAIM**

The ornamental design for a buffer with palm grip, as shown and described.

DESCRIPTION

FIG. 1 is a top-front-right perspective view of the buffer with palm grip showing our new design;

FIG. 2 is a front view of the design shown in FIG. 1;

FIG. 3 is a back view of the design shown in FIG. 1;

FIG. 4 is a right side view of the design shown in FIG. 1;

FIG. 5 is a left side view of the design shown in FIG. 1;

FIG. 6 is a top view of the design shown in FIG. 1; and,

FIG. 7 is a bottom view of the design shown in FIG. 1.
